LIGHT BEAM TRANSMISSION SYSTEM

Alexander McLean Nicolson, New York, N. Y., assignor to Communication Patents, Inc., New York, N. Y., a corporation of Delaware

Application April 13, 1934, Serial No. 720,449

4 Claims. (Cl. 250—7)

This invention relates to signalling systems and particularly to such systems employing a light beam or beams as the transmission medium.

An object of the invention is to transmit signals from point to point on modulated light beams.

Another object of the invention is to transmit a plurality of differently modulated light beams along a common transmission path and selectively separate said beams at a receiving point.

10 A further object of the invention is to transmit signals on invisible light beams over common transmission paths and select said beams on the basis of light intensity variations.

15 A still further object of the invention is to re-transmit signals on light beams in different directions to a plurality of receivers.

It is realized that signal transmission on light beams has been accomplished, the beams being modulated at the transmitter in accordance with 20 a particular signal and reproduced at the receiving station by means of a light sensitive device feeding the proper reproducing device. The present invention, however, contemplates multiplex transmission of a plurality of signals over a common 25 light beam or a light beam having a definite path, thus accomplishing multiplex transmission over a system that has heretofore been suitable for only a single channel. The invention contemplates two methods of and means for accomplishing this result, in one of which selection is 30 obtained on the basis of light frequency, and in the other on the basis of the frequency of interruption of the light beam.

The first method employs light filters which 35 produce a substantially monochromatic light beam for each signal, this monochromatic light beam being combined with others into a single beam for transmission over a common path. At the receiver the different beams may be separated by light filters, reception taking place in the usual manner. Partial reflectors may be inserted along the light path and the signal intercepted and delivered to other receivers. The second method employs electrical oscillators which

45 vary the intensity of a light beam in accordance with the oscillator frequency. Separation is obtained at the receiver by electrical filters after the light has been translated into electrical currents. Any type of signal may be transmitted 50 on either system and the systems may be combined. The invention will be more completely understood by reference to the following detailed description read in conjunction with the accompanying drawing in which:

55 Fig. 1 is a diagrammatic drawing of a multi-

plex system in which selection is made on the basis of light frequency, and

Fig. 2 is a diagrammatic drawing of a signalling system in which selection is made on the basis of the frequency of light intensity variations.

Referring to Fig. 1 in detail, three different signal sources are shown, these sources being illustrated as a microphone 5, a radio receiver antenna 6, and a television transmitter 7, signals from which are amplified in respective amplifiers 8, 9, and 10. The outputs of the amplifiers are connected to three light producing tubes 13, 14 and 15, respectively. These tubes may be of the crater type and filled with a gas which produces a light differing from the others. That is, tube 13 may contain hydrogen or neon and provide predominantly blue light, tube 14 may contain mercury or carbon dioxide and provide predominantly green, and tube 15 may contain acetylene and provide predominantly red. It is also within the scope of this invention to use other modulating means such as a constant intensity light source together with any light valve well known in the art. To increase the selection between the colors and the separation between signals, selective filters 17, 18 and 19 may be employed which will eliminate the undesired light frequencies. The three light beams, (it being understood that other monochromatic beams may be added without departing from the invention) may be joined optically in any well known manner by the use of prisms such as 22 and 23 and lens 24 cooperating with prisms 25 and 26. These light beams may be confined and directed in a beam by a lens 27, it being understood that the rays may be intermingled or kept along adjacent paths by the optical adjustment of the prisms and lenses, the light sources being removed from the focus of lens 27 by the use of lenses such as 24,

40 At the receiver a lens 30 in conjunction with prisms 31, 32, 33 and 34 and lens 35 separate the light beam into portions or different paths. The desired monochromatic light is then obtained by passing through filters 37, 38 and 39, 45 where it impinges upon respective photo cells 41, 42 and 43. These cells may be chosen according to their light frequency response characteristics. For instance, a caesium cell would function to aid the selectivity of the system in 50 the case of red light, a sodium or potassium cell would be more suitable for blue light, while a rubidium cell would be more sensitive to green light. The outputs of the cells may be amplified in amplifiers 45, 46 and 47, respectively, and 55

the outputs thereof impressed on any desired translating device, such as a sound reproducing device 48, transmitting device 49, or television receiver 50. That is, the microphone 5 is connected with the sound reproducer 48, the television transmitter 7 with its receiver 50, while the middle channel may be a re-broadcast circuit.

To illustrate the light broadcasting principle, a partial reflector 55 is shown positioned in the light beam, the light reflected therefrom being focussed by a lens 56 on a photo cell 57 after selection by a filter 60. The energy from the cell may be amplified in an amplifier 58 and retransmitted over antenna 59. It is also obvious that receivers may replace the antenna 59 and that other reflectors may be positioned in the light path for utilizing a portion of the transmitted energy.

From the description of the above system, it is obvious that selectivity is obtained on the basis of light frequency. The visible light spectrum contains a plurality of frequencies which when separated into individual frequencies provide different colors, each color representing substantially a single frequency. These rays are separately modulated, then mixed with other rays for transmission over a common transmission path, and then separated by light filters. Beams of composed light may also be refracted into their predominant spectra and signals thereof transmitted and received so as to use all concentrated energies in corresponding spectra. Although only three channels have been illustrated, using visible light rays, invisible light rays may also be used as a transmission medium, the invisible light forming a channel or channels simultaneously with the visible rays. With invisible light rays, of course, it would be necessary to use appropriate filters, an ultra-violet filter for ultra-violet light, etc., or corresponding invisible refracted light spectra.

Referring now to Fig. 2, a similar system is shown using a microphone signal source 65, and a television signal source 66, each of which have respective amplifiers 67 and 68. The output of the amplifiers feed glow tubes 70 and 71, these tubes being of a somewhat different type from those in Fig. 1. That is, tubes 70 and 71 are of the U-type which have wound around their straight sections windings 72 and 73, respectively, these windings being connected to respective oscillators 74 and 75. Oscillators 74 and 75 should operate at different frequencies, such as f_1 and f_2 , these frequencies being relatively high and above any of the signalling frequencies with which they are used. Their purpose is to vary the intensity of the light from the tubes at the frequencies of the oscillators. The tubes are modulated by the incoming signals being impressed upon the electrodes thereof. The light from these tubes may be the same and invisible, such as infra-red for instance, or may be different and visible frequencies or a combination of both. Other types of modulation may be used in this system as in Fig. 1, that is, well known mechanical shutters, such as perforated disks, may be placed before a constant light source and the light impulses modulated by a light valve.

The light beams from the tubes are collected by lens 80 and 81 and directed into a substantially common path by prisms 82, 83, 84 and 85, and then concentrated for projection by a lens 86. At the receivers a gathering lens 87 cooperating with prisms 88, 89, 90, 91 and lens 92 and 75 93 separate the beam into different portions and

positions and impress the different portions on photosensitive devices 95 and 96. These cells are connected to filters 97 and 98, respectively, which feed respective amplifiers 99 and 100, the outputs thereof being impressed on the proper receiving device, such as a sound reproducer 101 and a television receiver 102.

In the system of Fig. 2 selection is obtained on the basis of frequency of light interruption and as this light frequency is translated by the photo cells 95 and 96 into electrical currents having the same frequency, electrical filters may be used to select the signals by selecting the proper frequency. Although two systems have been described to illustrate the two methods of apparatus for the separation on the basis of light frequency and light interruption frequency, it is to be understood that these two systems may be combined into one so that both methods may be operated over the same light beam path. Such systems are especially desirable for use by amateurs inasmuch as there is no interference with radio transmission by heterodyning. Such systems are also desirable for secret signalling or for signalling over short distances where a large number of messages must be confined to a few channels.

What is claimed is:

1. A plural channel signaling system comprising means for generating a plurality of electrical currents representing individual signals, means for generating light waves, means for impressing said electrical currents directly on said last mentioned means to vary the amplitude of said light waves in accordance with the variations in amplitude of said currents, means for collecting and projecting said light to a distant point in the form of adjacent beams, means at said distant point for separating said adjacent light beams into spatially disposed beams, and means in each of said beams for eliminating substantially all light frequencies except a certain desired frequency.

2. A plural channel signal system in accordance with claim 1 in which said light waves are generated by glow tubes predominating in mutually exclusive frequencies and upon which said electrical currents are impressed, and said last mentioned means comprises filters selective of the respective frequencies generated by respective tubes.

3. A plural channel signaling system comprising means for generating a plurality of different electrical signals, means for generating light frequencies, said means directly translating said signals into corresponding variations in light intensities and distinguishing between said signals on the basis of light frequencies, means for collecting said light frequencies into adjacent beams and for optically projecting said adjacent light beams to a distant point, means at said distant point for spatially dividing said adjacent light beams, means at said distant point for segregating respective frequencies, and means at said distant point for translating said respective light frequencies into electrical currents having amplitude variations corresponding to the amplitude variations of said respective light frequencies.

4. A plural channel signalling system comprising means for generating a plurality of different electrical signals, means for translating said signals into corresponding variations in light intensities, said means distinguishing between said signals on the basis of light frequencies, means for collecting said light frequencies into adja-

cent beams and for optically projecting said adjacent light beams to a distant point, means at said distant point for spatially dividing said adjacent light beams, means at said distant point 5 for segregating respective frequencies, means at said distant point for translating said respective light frequencies into electrical currents having

amplitude variations corresponding to the amplitude variations of said respective light frequencies, and means intermediate the transmission and distant points for intercepting a particular desired signal without preventing the transmission thereof to said distant point. 5
